CLAIM

The ornamental design for a load cover, as shown and described.

DESCRIPTION

FIG. 1 is a top left perspective view of a load cover showing my new ornamental design with a phantom strap(not claimed) attached thereto and a typical strap next to it. The random criss-cross pattern on the body of the cover is understood to be represented throughout the entire area. FIG. 2 is a top plan view of the cover without strap(s); FIG. 3 is a side elevation of the cover without strap(s); and, FIG. 4 is an end elevation of the cover without strap(s).
